UNITED STATES PATENT OFFICE.

JOSEPH H. HOADLEY, OF NEW YORK, N. Y.

METHOD OF TRANSPORTING AND UTILIZING FUEL.

1,039,399.

Specification of Letters Patent. Patented Sept. 24, 1912.

Application filed June 2, 1911. Serial No. 630,923.

To all whom it may concern:

Be it known that I, JOSEPH H. HOADLEY, a citizen of the United States of America, residing in the borough of Manhattan, city of New York, county and State of New York, have invented a new and useful Method of Transporting and Utilizing Fuel, of which the following is a specification.

My invention relates to a novel method

10 for conveying or transporting fuel in the form of powdered coal in bunkers and drawing the fuel from the bunkers, conveying it toward, and injecting it into the furnaces.

By my method safety is insured and manual labor is eliminated.

I have devised different means for conveying my invention into effect; in some vessels the bunkers, or coal compartments, are on the side; in other vessels they are located entirely in the lower hold at the very bottom of the ship. My invention can be applied and adapted to both conditions.

I will proceed to describe my invention more specifically and will employ illustrative drawings to explain the different means which I utilize to consummate same.

Referring to the accompanying drawings which form a part of this specification,—Figure 1—represents a plan view of a portion of a steam ship showing my invention applied. Fig. 2— is a transverse section on the line II—II Fig. 1. Fig. 3— is a plan view showing a modification of my invention where it is applied to ships carrying coal only, or mainly, in the bottom hold. Fig. 4— is a vertical section on the line IV—IV, Fig. 3. Fig. 5— is a vertical cross section on the line V—V, Fig. 3. Fig. 6— is a similar section on the line VI—VI looking toward the furnaces.

In this drawing 1 represents the hull of a steamship or vessel. In Fig. 1 is shown a series of bunkers or compartments 2. At 3 I show an opening at the top of the bunkers through which the fuel or powdered coal can be introduced; and at 4, covers for the said openings, or ports, by means of which the compartments can be tightly sealed so that air cannot pass in, or out, at this point. Any suitable means of sealing may be employed, but it must be effectual in this respect as the operativeness and efficiency of my invention depends absolutely upon this phase of it being carried into proper effect.

55 In the form of bunkers shown in Figs. 1 and 2, the bottom is arranged on a slant, as

shown at 5, the inclination being from the outward to an inward line and terminating at the point 6; 7 being the inner wall of the bunkers.

60 The bunkers, or compartments, herein shown are utilized for the joint purpose of transportation and usage in transit; they constitute the depository of the coal used for the furnaces on the ship.

65 In carrying my invention into effect, I desire, as before stated, to remove all the free oxygen so far as possible from the bunkers, or compartments, where the fuel may be stored; and I show in the drawings herein 70 ways of accomplishing this purpose.

Referring to Fig. 1, I show at 8 a battery of furnaces arranged in tandem and I purpose drawing off from the various bunkers 2, from time to time, such fuel as is necessary 75 for the said furnaces and introducing the fuel by a forced draft into the fire box 9. This may be accomplished in different ways and I do not limit myself to any particular means to carry this phase of my apparatus into effect.

At 10 I show a pipe connected to horizontal pipes 11, having branch pipes 12, the latter entering the tops of the compartments or bunkers. The lower end of the 85 pipe 10 is connected with horizontal pipe 13, the latter constituting the intake of pumps 15. Discharge pipes 14 lead from pumps 15 to fire box 9. When these pumps are set into operation by any suitable means 90 (not shown) the effect will be that the air in the upper part of the bunkers, or compartments 2, will be drawn off and forced by means of the said pumps into the fire boxes 9. In the first place by exhausting 95 the air from the bunkers, or compartments, I create partial vacuum therein, and so reduce the amount of free oxygen that spontaneous combustion is rendered impossible.

When the air has been exhausted from the bunkers, the cocks 16 can be closed and the cocks 17 can be opened, whereupon the air necessary for creating the forced draft by virtue of the pumps 15 can enter through the pipes 18, and from thence into the pipes 10; and so on to the pumps; in operation however I preferably keep cocks 16 slightly open so that at all times the efficiency of the vacuum is maintained.

110 It will be seen that I provide alternative sources for the air to be used for the forced draft, and after the air has been exhausted

from the bunkers, or compartments, I can draw the necessary amount from the outside air without stopping the operation of the apparatus through the manipulation of the parts just described.

- 5 I prefer in the employment of my method to introduce the powdered coal into the bunkers, or compartments, through the opening 3, in a wet, or moistened, condition. 10 This envelop of moisture is in itself an insurance of safety as it decreases the possibility of spontaneous, or accidental combustion, and I may, and in some cases do, utilize this same principle after the fuel has 15 been introduced into the bunkers, or compartments, by directing either live or exhaust steam therein. Such a device is shown in Figs. 1 and 2 of the drawings.

At 19 is a pipe receiving live or exhaust 20 steam from any suitable source, and leading off from this pipe 19 are branch pipes 20 terminating in coils 21, which may be either just inside or just outside of the bottom bunkers. Stop cocks 22 can regulate or cut 25 off the supply of steam to the coils; and at 23 I show vertical pipes which form the terminal of the coils and which extend upward in the bunkers and terminate at a point just inside of the covers.

30 The coal is withdrawn at the lower terminals of the bunkers through pipes 24, and the coils 21 can be utilized for heating the lower terminals of the bunkers and driving off the moisture from the coal, if any still 35 exists, as it is desirable to withdraw the coal for immediate consumption in a fairly dry condition and the steam passing out of the coils can enter the tops of the bunkers through the terminal pipes 23 and serve to 40 keep the upper portion or body of the coal in a partially moist condition.

If the supply of steam permitted to flow 45 through the coils 21 and then through the pipe 23 into the upper part of the bunkers, 2, is shut off, a condensation will gradually 50 ensue and this will also tend to create a vacuum, or a partial vacuum. If the steam is entering any particular bunker and the pumps, 15, are not drawing on that particular one, any tendency to an accumulation of steam in the bunkers can be obviated by a safety valve, 25.

In the form shown in Figs. 1 and 2, the powdered fuel is withdrawn from the bottom 55 of the bunkers through the pipes 24. Upon opening the cocks, 26, the fuel will flow out and deposit itself upon the traveling belts 27. These belts are mounted upon drums, 28, and travel in the direction of 60 the arrow. The air intake pipe 13 is provided with an opening 29, and said opening together with the discharge opening of pipe 24, and the belts 27 are inclosed by a casing 30. Means are provided for removing 65 the coal from the belts 27; for this pur-

pose I employ the plates 31 set at an angle within the casing 30, which, as the coal moves along, direct it onto an inclined plate 32, from which it slides into openings 29 in pipe 13 and is drawn by pumps 15 and 70 forced with the accompanying air into the fire boxes.

The form shown in Figs. 1 and 2 is desirable and feasible in some steamships and particularly in naval vessels where, in many 75 instances, the bunkers are arranged upon the sides. In other steamships the bunkers are arranged entirely in the lowermost hold, and I have adapted my invention to vessels of this construction also.

80 In Figs. 3 to 6, inclusive, I have shown the design and arrangement of bunkers and furnaces as employed by the Cunard Line and notably in the *Campagna* and its sister ship. In these ships the coal is carried in 85 the lowermost hold and it is necessary to draw it up and out of these compartments and introduce it the same as I have shown it in connection with the other form, or arrangement.

90 At the bottom of the bunkers, 2, I place a worm screw, 33, which may be operated from any suitable source and which when turning draws the coal forward and deposits it on the belts 23, conveying it to the 95 central chamber 35, into which there is directed a series of buckets 36 mounted on the belt 37 and adapted to seize the fuel and carry it upwardly, as indicated by the arrows in Fig. 4, and deposit it in a centrally 100 located hopper 38. This hopper terminates at its lower end in branches 39 which are adapted to deposit the fuel on the belts 40; and from this point on the operation of the device is the same as in the construction 105 shown in Figs. 1 and 2. In both cases I have illustrated my novel method for transporting and utilizing fuel.

In employing my invention I preferably 110 use the bunkers in succession and permit those from which the fuel is not being withdrawn to remain intact and undisturbed with the understanding that I preferably 115 use continuous means for maintaining the bunkers free from the presence of oxygen.

115 The steam employed for pre-heating the coal about to be withdrawn from any bunker for use can be exhaust steam from any of the engines, or it can be live steam if preferred.

120 Where steam has been introduced in any manner into the bunker, it can, if desired, be permitted to condense and this condensation will result in a vacuum, or partial vacuum.

125 In these methods and processes it is to be understood that the acts are coöperative in their nature, that is to say, the gases and the coal are withdrawn by coöperating instrumentalities through separate channels.
